DESIGN FOR A MULTIPLE TOOL

Ellsworth B. Overshiner, Chicago, Ill., assignor
to Electra Voice Corporation, Chicago, Ill., a
corporation of Delaware

Application May 10, 1946, Serial No. 129,551

Term of patent 14 years

(Cl. D54—13)

To all whom it may concern:

Be it known that I, Ellsworth B. Overshiner, a citizen of the United States, residing at Chicago, Cook County, Illinois, have invented a new, original, and ornamental Design for a Multiple Tool, of which the following is a specification, reference being had to the accompanying drawings, forming a part thereof:

Fig. 1 is a plan view of one side of a multiple tool, showing my new design;

Fig. 2 is a plan view of the other side thereof;

Fig. 3 is an elevational view of the bottom edge of Fig. 2; and

Fig. 4 is an end view of the right end of Fig. 1.

I claim:

The ornamental design for a multiple tool, as shown.

ELLSWORTH B. OVERSHINER.
